APPLYING METAL BANDS TO ARTICLES OF
MANUFACTURE

Herman A. Bondeson, Providence, R. I., assignor
to Standard Machinery Company, Cranston,
R. I., a corporation of Rhode Island

Application January 7, 1941, Serial No. 373,478

3 Claims. (Cl. 78—15)

The present invention relates to a method of and apparatus for attaching rings or bands to articles of manufacture.

Although the method and apparatus of the present invention are of general application they are particularly adapted for attaching rotating bands to projectile shells. The projectile shells used with larger caliber guns, such as one inch to eighteen inches, have rotating rings or bands of relatively soft material encircling their peripheries. When the shell is propelled through the gun the rifling lands in the bore cut into the rotating band on the shell and due to the helical form of the lands cause the shell to rotate during its forward movement through the gun. Heretofore, the rotating band has usually been crimped on the projectile shell but such a crimped band is apt to be loosely attached to the shell, preventing its proper rotation, and is liable to become disconnected from the shell due to centrifugal force after the shell leaves the gun-barrel. Moreover, such a crimped rotating band does not have a uniform outside diameter.

One of the objects of the present invention is to provide a method of and apparatus for attaching a band or the like to an article of manufacture, such as a projectile shell, by swaging the band around its entire periphery to compress it to a smaller diameter to grip the periphery of the shell or other article.

Another object of the invention is to provide a method of and apparatus for attaching a band to an article of manufacture by compressing and deforming the material of the band to cause it to interlock with serrations on the article and conform to a uniform diameter at its periphery throughout its length.

Another object of the invention is to provide an apparatus of the type indicated which will facilitate the attaching of bands to articles of manufacture and one which is adapted to be operated by unskilled workmen.

Another object of the invention is to provide an apparatus of the type indicated adapted to support the article with the band properly positioned thereon while feeding it into a rotary swaging head.

Another object of the invention is to provide an apparatus of the type indicated having a mandrel for supporting the article and a relatively movable sleeve for initially positioning the band on the article and ejecting the article from the mandrel after the band has been attached thereto.

Still another object of the invention is to pro-

vide an apparatus of the type indicated which is of simple and compact construction to render it economical to manufacture and one which is adapted for use over long periods of time without requiring repair or replacement of its parts.

Further objects of the invention are set forth in the following specification which describes a preferred embodiment of the invention, by way of example, as illustrated by the accompanying drawings. In the drawings:

Fig. 1 is a side elevational view partly in section of an apparatus incorporating the novel features of the present invention;

Fig. 2 is a transverse sectional view taken on line 2—2 of Fig. 1 showing the means for actuating the hammers of the rotary swaging head;

Fig. 3 is an enlarged longitudinal sectional view of a part of the apparatus showing the initial deformation of a rotating band by the rotary swaging head and the engagement of the positioning sleeve with a fixed stop or abutment;

Fig. 4 is a view similar to Fig. 3 showing the rotating band completely deformed by the rotary swaging head and illustrating the flow of the material of the band beyond the rearward end of the recess in a shell;

Fig. 5 is a view similar to Fig. 4 showing the shell retracted and the end of the positioning sleeve in engagement with the end of the rotating band to cause the shell to be ejected from its mandrel;

Fig. 6 is a side view of the finished shell shown partly in section; and

Fig. 7 is a side view of the shell with the rotating band illustrated in section to show the serrations at the bottom of the recess and indicating the manner of initially applying the rotating band to the shell.

In accordance with the method of the present invention the article of manufacture, herein illustrated as a projectile shell 2, is provided with a peripheral groove or recess 3 as illustrated in Fig. 7. Preferably, the bottom of the recess 3 is knurled or serrated as indicated by the reference character 4 in Figs. 6 and 7 to provide an irregular surface. The band 5 to be attached to the shell 2 is composed of relatively soft material, such as copper or a suitable alloy, and has an inside diameter of such dimension as to adapt it to slide over the periphery of the shell. The forward end of the rotating band 5 is aligned with the forward end of the recess 3 in the shell 2 and swaged around its entire periphery to deform and compress the rotating band to seat its forward end in the recess in the

shell, see Fig. 3. The swaging action is then advanced axially to cause the entire band to be deformed and compressed. Due to the relatively soft material of the rotating band and its deformation, due to the swaging, the material flows into the interstices between the serrations 4 to cause it to tightly grip the shell. Preferably, a surplus amount of material is provided in the rotating band 5 whereby the deformation of the band due to the swaging operation causes the material to entirely fill the recess 3 and to flow a short distance beyond the rearward end of the recess and form a flange or fin 6, see Fig. 5. After the rotating band 5 has been swaged to the shell the flange or fin 6 is preferably trimmed off to aline the rearward edge of the band with the rearward edge of the recess 3 in the shell 2. The rotating band so attached then projects outwardly beyond the periphery of the shell and has its outer surface of uniform diameter throughout its length. It will be understood that the band 5 may have other forms, such as a ferrule, oil ring, bushing or the like and may be attached to other articles of manufacture either in a recess or on the periphery thereof.

Referring to the present drawings, a novel form of machine or apparatus is illustrated therein for carrying out the steps of the above described method. The frame 10 of the machine supports a rotary swaging head 11 and projecting laterally therefrom is a bracket or arm 12 for supporting a feeding mechanism 13 for advancing the shell and rotating band into the rotary swaging head 11. The rotary swaging head 11 comprises a drive shaft 14 having an enlarged end-portion 15 with a radial slot 16 extending across its axis, see Figs. 1 and 2. Slidably mounted in suitable bearing-guides at the sides of the slot 16 is a pair of opposed hammers 17 and 18 having their outer ends 19 and 20 of arcuate contour. Between the hammers 17 and 18 is a pair of dies 21 and 22 having semi-cylindrical recesses 23 and 24 which flare outwardly toward the forward face of the dies with a gradual taper as indicated at 25 and 26 in Fig. 1. Surrounding the enlarged end-portion 15 of the drive shaft 14 is a relatively stationary cage 30 supporting rollers 31 held in pockets in circumferentially spaced relationship. As the drive shaft 14 is rotated at a relatively high speed the hammers 17, 18 successively move radially outwardly between the rollers 31 due to centrifugal force and then are forced radially inwardly due to the engagement of their arcuate ends 19 and 20 with the rollers 31 whereby a rapid succession of blows is transmitted to the dies 21 and 22. Abutting the ends of the rollers 31 are retaining rings 32 and 33 and surrounding the cage 30 is a head ring 34. Adjacent the retaining rings 32 and 33 are thrust rings 35 and 36. At the front of the rotary swaging head 11 is a door 37 having a reentrant orifice 38 for guiding the work into the flared opening at the front of the dies 21 and 22.

The feeding mechanism 13 comprises a ram or feed member 42 slidably mounted in the longitudinally extending bore of a bearing 40 mounted on the arm 12 which projects from the frame 10. The feed member 42 has rack-teeth 43 formed on its under side which mesh with a pinion gear 44 mounted on a shaft 45 extending transversely of and journaled in the bearing 40. At the outer end of the shaft 45 is a capstan-wheel 46 for turning the pinion gear 44 to traverse the feed member 42. Extending through a

central bore in the feed member 42 is a mandrel-supporting plunger 47 rotatably mounted in suitable bushings 48, see Figs. 1 and 3. Supported on a rod 53 extending rearwardly from the bearing 40 is brake-band 54 engaging a disk 55 for restraining the mandrel-supporting plunger 47 against rotation relatively of the feed member 42 while permitting a limited oscillation of the plunger. The mandrel-supporting plunger 47 is prevented from longitudinal movement with respect to the feed member 42 by means of collars 49 and 50 on the plunger which abut the ends of the member. The forward end of the feed member 42 is slightly enlarged to provide an annular shoulder 56.

A mandrel 57 is mounted on the forward end of the plunger 47 and has a contour corresponding to the contour of the powder-chamber 58 of the shell 2 to adapt it to fit closely therein. It will be understood that the mandrel 57 may have other forms to adapt it to support other articles besides the shell 2 illustrated in the drawings. Preferably, the mandrel-supporting plunger 47 and mandrel 57 have alined longitudinally extending bores 59 and 60 to permit a small rod or the like to be inserted therethrough to drive a shell 2 off from the mandrel when necessary.

Surrounding the forward end of the mandrel-supporting plunger 47 is a positioning sleeve 64 having a stepped bore 65 of considerably larger diameter than the diameter of the plunger 47 to provide an annular opening therebetween. The rearward end of the sleeve 64 closely fits around the enlarged forward end of the feed member 42 and has an annular ring 66 fastened thereto by means of screws 67 for engagement with the annular shoulder 56 on the member. At its forward end the sleeve 64 has a bore 68 of such dimension as to closely fit the mandrel-supporting plunger 47. Thus the sleeve 64 is slidably mounted on the feed member 42 and the mandrel-supporting plunger 47 and has a support at either end. Detachably mounted on the forward end of the sleeve 64 by means of a screw-threaded connection at 63 is a tip-member 69 having a central bore 70 of such dimension as to adapt it to receive the shell 2 between it and the mandrel 57. The forward end of the tip member 69 is adapted to extend to the rearward end of the recess 3 in a shell 2 when the latter is properly positioned on the mandrel 57 whereof to engage the rotating band 5 and position its forward end in alinement with the forward end of the recess. It will be understood that interchangeable tip members 69 may be provided for use with different types of work, or with shells of different forms or caliber having the recess 3 at a different location. A lock-washer 71 is provided between the end of the sleeve 64 and a shoulder on the tip member 69 to retain the latter in position thereon.

The sleeve 64 is normally held in its forward position, illustrated in Fig. 3, by means of a helical spring 72 acting between the forward end of the feed member 42 and the annular shoulder 73 at the end of the stepped bore 65 in the sleeve. Thus the sleeve 64 is adapted to advance with the feed member 42 and mandrel-supporting plunger 47 but is movable with respect thereto against the action of the spring 72. Adjustable on a screw-threaded portion 74 of the sleeve 64 is a nut 75 which may be locked in any desired position of adjustment by a lock-nut 76. A stationary abutment 77 fixed to the cover 37, see Fig. 1, is positioned in the path of movement of

the nut 75 when the mandrel 57 has been advanced to the position illustrated in Fig. 3, whereby the tip member 69 of the sleeve 64 is prevented from further movement into the rotary swaging head. One embodiment of the invention having now been described in detail the mode of operation of the apparatus is explained as follows:

With the parts of the apparatus in their relative positions illustrated in Fig. 1 a shell 2 with a rotating band 5 loose thereon is mounted on the mandrel 57 by sliding it rearwardly from the position illustrated in dash lines in Fig. 1 to that illustrated in Fig. 3. When the shell 2 is properly mounted on the mandrel 57 the rearward end of the rotating band 5 will be engaged by the forward end of the tip 69 mounted on the sleeve 64 to position the forward end of the rotating band in alignment with the forward end of the recess 3 in the shell.

The capstan-wheel 46 is then turned in counterclockwise direction as viewed in Fig. 1 whereby the pinion gear 44 and rack-teeth 43 on the feed member 42 will cause the latter to advance axially through the bearing 40 toward the rotary swaging head 11. Advancement of the feed member 42 simultaneously advances the mandrel-supporting plunger 47 and the mandrel 57 carried thereby due to the engagement of the end of the feed member 42 with the collar 49 on the plunger. Thus the shell 2 and the rotating band 5 thereon will be advanced with the mandrel 57 to cause them to enter the flaring mouth 25, 26 of the dies 21 and 22 as shown in Fig. 3. As the shell 2 and rotating band 5 are advanced between the dies 21, 22 the latter are being rotated at a relatively high speed by the drive shaft 14 and the engagement of the arcuate ends of the hammers 17 and 18 with the successive rollers 31 will cause the dies to be reciprocated toward and away from each other in rapid succession. The engagement of the forward end of the rotating band 5 with the rapidly reciprocating dies 21 and 22 will consequently deform the band as indicated in Fig. 3. As the shell 2 and rotating band 5 continue to be advanced into the rotary swaging head 11 the gradually reduced diameter of the flared mouth 25, 26 of the dies 21, 22 causes compression of the rotating band until it entirely fills the recess 3 when the shell reaches the position illustrated in Fig. 4. Simultaneously with the compression of the rotating band 5 the material thereof is caused to flow into the interstices between the serrations 4 in the bottom of the recess 3 whereby the rotating band firmly grips the shell, see Fig. 6. Preferably, the rotating band 5 has a surplus of material to assure complete filling of the recess 3 in the shell 2 and to also cause a part of the material to flow beyond the rearward edge of the recess to form a thin fin or flange 6, see Fig. 4.

As the forward end of the rotating band 5 becomes completely compressed into engagement with the bottom of the recess 3 in the shell 2 the nut 75 on the sleeve 64 will bring up against the fixed stop 77 on the cover 37, see Figs. 1 and 4. Any further longitudinal movement of the feed member 42 by the rotation of the capstan-wheel 46 will cause the mandrel 57 and mandrel-supporting plunger 47 to advance relatively of the sleeve 64, the compression of the spring 72 permitting such relative movement.

After the shell 2 has been forced through the dies 21 and 22 to swage the rotating band 5 along its entire length the capstan-wheel 42 is rotated in clockwise direction to reverse the direction of

movement of the feed member 42 to withdraw the shell 2 from the swaging head 11. This movement is continued until the fin or flange 6 at the end of the rotating band 5 engages the end of the tip member 69 of the sleeve 64. Further rearward movement of the mandrel 57 and mandrel-supporting plunger 47 with respect to the sleeve 64 will cause the shell 2 to be forced off from the mandrel 57, the spring 72 having sufficient tension to eject the shell under normal conditions in the manner indicated in Fig. 5. Continued rearward movement of the feed member 42 with respect to the sleeve 64 will cause its shoulder 56 to bring up against the ring 66 at the rearward end of the sleeve whereof the sleeve 64 and feed member 42 will thereafter move rearwardly as a unit to restore the parts to first position.

Although not entirely essential, preferably the fin or flange 6 at the rearward end of the rotating band 5 is removed by a trimming operation in any suitable machine, such as a lathe. The shell 2 will then be partially completed with a rotating band compressed along its entire length and swaged inwardly to completely fill the recess 3 in the shell and grip the serrations 4 at the bottom of the recess. When applied in the manner as above explained the rotating band will have a smooth continuous outside surface of uniform diameter throughout its length.

It will be observed from the foregoing specification that the present invention provides a novel method of and apparatus for applying bands, rings or the like to articles of manufacture by swaging the bands around their entire peripheries. It will also be observed that the apparatus of the present invention is of relatively simple construction to adapt it for economical manufacture and to enable it to be operated by unskilled workmen to carry out the present improved method of applying bands to projectile shells or similar articles of manufacture.

While an improved method and a preferred form of apparatus are herein described and illustrated it will be understood that modifications may be made in the steps of the method and in the form and arrangement of the parts of the apparatus without departing from the spirit or scope of the invention. Therefore, without limiting myself in this respect, I claim:

1. In an apparatus for attaching a band to an article of manufacture having a peripheral recess, the combination of a rotary swaging head, a mandrel for supporting the article in axial alignment with the swaging head, a sleeve slidable on the mandrel and engageable with the rearward end of the band to align its forward end with the end of the recess in the article, means for advancing the mandrel and sleeve until the band enters the swaging head, and means engaging the sleeve for holding it against further movement with the mandrel.

2. In an apparatus for attaching a rotating band to a projectile shell having a peripheral recess, the combination of a rotary swaging head, a mandrel for supporting the projectile shell in axial alignment with the swaging head, a sleeve slidable on the mandrel and adapted to position the rotating band in alignment with the recess in the shell, a spring for yieldingly holding the sleeve in proper position on the mandrel, means for advancing the mandrel and sleeve toward the swaging head, and a stationary abutment for engaging the sleeve during its advance to hold it against further movement with the mandrel.

3. In an apparatus for attaching a rotating

band to a projectile shell having a peripheral recess, the combination of a rotary swaging head, a mandrel for supporting the projectile shell in axial alinement with the swaging head and having an annular shoulder, a sleeve surrounding the mandrel and having a shoulder engageable with the shoulder on the mandrel, a spring between the mandrel and sleeve for normally holding the cooperating shoulders on the two parts in engagement, said spring being adapted to yield to permit relative longitudinal movement between the man-

drel and sleeve, means for advancing the mandrel and sleeve toward the swaging head, a stationary abutment engaged by the sleeve after the projectile shell and rotating band have entered the 5 swaging head, said swaging head operating to deform the rotating band to cause it to enter the peripheral recess in the shell, and said sleeve engaging the deformed rotating band when the 10 mandrel is withdrawn from the swaging head to eject the shell from the mandrel.

HERMAN A. BONDESON.
